Primary Examiner — April Rivas(74) *Attorney, Agent, or Firm* — Banner & Witcoff, Ltd.(57) **CLAIM**

The ornamental design for a bag, as shown and described.

DESCRIPTION

FIG. 1 is a top, front, right perspective view of a bag showing our new design;

FIG. 2 is a top, front, right perspective view of an alternative claimed configuration of a bag thereof;

FIG. 3 is a top, front, right perspective view of an alternative claimed configuration of a bag thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The even-length broken lines and zig-zag lines represent stitching and form part of the claimed design. The broken lines immediately adjacent to the shaded area represent unclaimed subject matter.
